YARN CARRIER FOR KNITTING MACHINES

Russell D. Curry, Downingtown, Pa.

Application July 6, 1948, Serial No. 37,227

5 Claims. (Cl. 66—126)

1

This invention relates to yarn carriers for knitting machines. More specifically, it is concerned with yarn carriers of the traversing finger variety universally used, for example, in connection with straight knitting machines designed for the production of flat fashioned hosiery blanks, and having guide tubes at their lower ends to lay the yarns across the nibs of transversely slurred sinkers incident to feeding the yarns to the needles of the machines.

In carriers of the kind referred to, as ordinarily constructed, the guide tubes are rigidly secured to the fingers. Thus in the event that a sinker or sinkers be accidentally displaced upward or any other abnormal obstruction be inadvertently thrust into the path of the tube, so called "smash ups" would occur with severe damage to the machine parts. These smash ups are very costly, not only from the standpoint of the value of the replacements which must be made and the labor involved, but also by reason of the enforced idling of the machines for the repairs.

The chief aim of my invention is to overcome the above drawbacks, which desideratum I attain, as hereinafter more fully disclosed, through provision of means whereby the guide tubes are yieldingly supported in the ends of the fingers with capacity to swing aside upon impact with any abnormal obstruction in their paths irrespective of the direction of traverse.

Other objects and advantages will appear from the following detailed description of the attached drawings, wherein Fig. 1 is a view in front elevation of a yarn carrier conveniently embodying my invention.

Fig. 2 is an edge view of the device as seen from the right of Fig. 1 with the lower end thereof shown in central vertical section.

Fig. 3 is a perspective view of the guide tube of the carrier.

Figs. 4 and 5 are perspective views respectively of two spring bands whereby the guide tube is yieldingly supported on the carrier for the purpose hereinbefore stated;

Figs. 6 and 7 are horizontal sectional views taken as respectively indicated by the angled arrows VI—VI and VII—VII in Fig. 1.

As illustrated, my improved yarn carrier is in the form of a stiff flat finger which is generally designated 10, and which, at the top, has a widened head portion 11 with holes for passage of screws 12 whereby it is secured to a holder A on a longitudinally reciprocating carrier bar B of the knitting machine after common practice in the art. At its bottom end, the finger 10 is

2

formed with an angular bight 13 having complementarily sloped side edges 14 and a relatively narrow square upward prolongation 15 in the longitudinal major axis of said finger.

Centrally located within the bight 13 and normally disposed in vertical position therein, is a guide tube 16 whereby the knitting yarn indicated at Y is laid across the nibs of the sinkers shown at S so as to be taken by the needles 10 (not shown) of the knitting machine as the finger 10 is traversed back and forth in the usual and well known way. From Fig. 3 it will be observed that the guide tube 16 is downwardly tapered somewhat and formed at the top 15 at one side with a flat face 17 and at the opposite side with a lateral hemispherical protuberance 18. As shown in Figs. 1, 2, 6 and 7 the tube is held assembled with the finger 10 by a pair of flat narrow spring bands 19 and 20 which are separately illustrated in Figs. 4 and 5. The band 19 is sprung about the lower end of the finger 10 approximately at the level of the crotch of the bight 13 with its opposite side portions spanning the gap 15, and is held against displacement within a crosswise groove 21 formed in said finger. Centrally of one of its parallel side portions, the band 19 is provided with a socket indentation 22 into which the lateral spherical protuberance 18 at the upper end of 20 the guide tube 16 fits. The band 20 extends about the finger 10 at a lower level and is similarly lodged in another crosswise groove 23 with its parallel side portions spanning the bight 13, said side portions being provided centrally with outwardly-rounded vertical axis bulges 24 which are downwardly tapered so as to lightly engage the guide tube 16 at a point medially of its ends and so normally prevent displacement thereof from the vertical position in which it is shown 40 in full lines.

As a consequence of this novel construction it will be seen that, when necessary due to wear or for any other reason, the tube 16 can be readily removed by dilation of the spring bands 19 and 20 and replaced by a new one. Furthermore, in the event that, during traverse of the carrier finger 10, the lower end of the tube should meet with an accidentally raised sinker or sinkers S or any other abnormal solid obstruction or 45 obstructions in its path, the band 20 will readily yield to enforced lateral spreading and so permit said finger to turn about the pivot 18 and swing aside in one direction or the other, as instanced in broken lines in Fig. 1, depending 50 upon the direction of travel of the carrier. Re-

tation of the tube 16 about its own axis is prevented through cooperation of its flat surface 17 with the straight frontal portion of the band 19 as will be readily seen from Fig. 6. Thus, through my invention, costly "smash ups," such as frequently occur under similar circumstances in straight knitting machines equipped with the ordinary types of yarn carriers, are effectively precluded.

Having thus described my invention, I claim:

1. A yarn carrier for straight knitting machines comprising a flat finger with a vertical axis angular bight in its lower end; a rigid guide tube for the yarn which is to be fed to the needles of the knitting machine; and retaining means for pivotally supporting the tube at its upper end within the top of the angular bight in the finger with capacity to swing aside from a normal central position within said bight in the event that it meets with an obstruction incident to the traverse of said finger in either direction.

2. A yarn carrier according to claim 1, wherein the guide tube has a lateral hemispherical protuberance adjacent its top end; and wherein the retaining means includes a flat spring band secured about the finger in the region of the top of the angular bight and having a socket indentation centrally of one of its side portions for engagement by the hemispherical protuberance at the top of the guide tube, and a second flat spring secured about the finger at a lower level and having bulge indentations centrally of its opposite side portions to lightly engage the guide tube at a point intermediate its ends.

3. A yarn carrier according to claim 1, wherein the guide tube has a lateral hemispherical protuberance at one side of its top end and a flat face at the opposite side; and wherein the retaining means includes a spring band which is secured

about the finger in the region of the top of the bight with its opposite side portions spanning the bight, one side portion of said band having a socket indentation centrally of one side portion for engagement by the hemispherical protuberance at the top of the guide tube and the other side portion being plain and abutted by the flat of said tube, and a second spring band secured about the finger at a lower level and having outward bulge offsets centrally of its opposite side portions for lightly engaging the guide tube adjacent its lower end.

4. As a new article of manufacture, a yarn carrier for flat knitting machines having the form of a flat finger with an angular bight in its lower end, and with a pair of spaced spring bands secured about the finger and spanning said bight, one at the level of the top of the bight and the other adjacent the end of the finger, and a guide tube pivotally connected at its top end within the upper band at the center and extending down through the lower band.

5. As a new article of manufacture, a guide element for knitting machine yarn carriers in the form of a rigid tube with a lateral pivot protuberance at its upper end, and a flat face at the side opposite said protuberance.
